UNITED STATES PATENT OFFICE.

NEWELL R. BARTLETT, OF SPRINGFIELD, MASSACHUSETTS.

LOCK BUTT FOR ASPHALT SHINGLES.

Application filed March 11, 1926. Serial No. 93,886.

This invention relates to improvements in lock butts for shingles particularly of the type of shingle known as prepared roofing which, in general, comprises a felt material that has been treated with asphalt to render it water-proof and the weather side having a surface composed of ground slate, crushed tile, or similar material. It is commonly known as an asphalt shingle.

10 A further object of the invention is to so form the butt ends of the shingles that they may be aligned accurately with each other.

A further object of the invention is to so 15 form the shingles that they may be firmly locked together at the butt end for covering the securing nails.

A further object is to securely lock the shingles together by means of one or more inturned tongues that will engage the lower 20 inclined edges at a point removed from the meeting corners or angles of the adjacent shingles. This permits the lower edges of the shingle to be easily raised and the locking tongues readily inserted thereunder and 25 the overlapping shingle drawn upward into the locking position. Heretofore it has been a common practice to form the shingle with a single tongue that is bent under the body of the shingle which tongue is inserted directly 30 under the meeting corners or angles of adjacent corners below the under layer. This construction is objectional on account of the difficulty in raising the lower shingles for inserting the tongue. Other locking devices are employed which do not extend 35 under the shingle. The invention, in general, comprises different forms or modifications of the locking tongues as will be set out in the body of the specification. The 40 invention embodies three thicknesses of the shingle material at the locking points.

Referring to the drawings:

Fig. 1 is a plan view of one of the shingles or blanks showing two slits in the corner 45 which intersect each other and extend beyond the point of intersection.

Fig. 2 is a similar view to Fig. 1 with the corner piece removed.

Fig. 3 indicates the two locking tongues 50 bent backward and under the body of the shingle.

Fig. 4 is a sectional view on the line 4—4 of Fig. 3.

Fig. 5 is a sectional view on the line 5—5 55 of Fig. 3 showing the bent under tongues.

Fig. 6 is a view of one of the under

shingles for laying at the eaves or lower edge of the roof.

Fig. 7 is a sectional view on the line 11—11 of Fig. 6. 60

Fig. 8 illustrates the manner of laying or assembling the shingle on a roof, two layers only being shown.

Fig. 9 illustrates a single row of the shingles before the upper layer is applied as 65 shown in Fig. 8, and.

Fig. 10 illustrates the layer at the lower or edge part of the roof employing the pieces as shown in Fig. 6. 70

Referring to the drawings in detail:

1 designates one of the shingle elements having the two slits 2 and 3 cut therein and parallel with the sides 4 and 5 which intersect at 2' and extend beyond the point of intersection, as shown. This cutting of the slits results in the removing of the rectangular corner piece 6 as illustrated in Fig. 2. The dotted lines 7 and 8 illustrate the folding or bending line of the locking tongue portions 9 and 10, which are folded under 75 the shingle part as indicated in Fig. 3 by the dotted lines 11 and 12 leaving the corner of the shingle with the projecting part 13. The bent under tongues 9 and 10 are shown in the sectional views in Fig. 4 and Fig. 5 80 85 or in other words these tongues are locking elements.

Fig. 6 illustrates one of the shingle elements having a portion that is folded under upon itself as indicated by the part 20. The lower corners of this are cut off at angles to the sides producing the ends 22 and 23. 22' and 23' are slits for receiving the locking tongues 9 and 10 when assembled. The 90 ends of these shingles are cut on the lines 22' and 23'. 95

Fig. 9 illustrates several of the shingle elements laid on a longitudinal line similar to the way they are laid on a roof with the apex or corner portions 24, 24 adjacent each other. 25 indicates the nails for holding the shingles 1 in place. Next, a second layer of shingles indicated in Fig. 8 by the numerals 1' is placed over the shingles indicated at 1. The locking tongue elements 9 and 10 100 are slipped under the lower edges 26 and 27. These locking tongues it should be stated are spaced some distance from the apex 28 when inserted whereby the edges 26 and 27 105 may be readily elevated and the tongues inserted under the shingles indicated at 1. The shingle 1' is then drawn upward into the 110

positions shown. The projecting part 13 then occupies the space between the lower edges 26 and 27. This part may be removed by punch cutters operating on the dotted lines 2" and 3" of Fig. 1.

It will be noticed that the shingles 1' overlap the securing nail heads 25. The notched edges of the shingles 1 which are parallel with the sides 4 and 5 permit the accurate alignment of the shingle elements 1 and 1' as the edges 29 and 30, see Fig. 8, are parallel with the sides 4 and 5 permitting accurate alignment with the edges 26 and 27 as shown in Fig. 8.

Referring to Fig. 10 which embodies the arrangement of the structure shown in Figs. 6 and 7 for the lower edge of the roof. The elements 1², see Fig. 6, several of which are arranged as shown with the bent under portion 20 and through which nails 25 are driven for securing these shingles in place. The next operation is placing one of the shingle elements 1' indicated in Figs. 1 to 3 over the elements 1² with the tongue portions 9 and 10 entering the slits 22' and 23' shown in Fig. 6. This layer of shingles 1' covers the nail heads 25 and effectually locks this upper layer to the lower layer 1². It will be seen therefore that there are three thicknesses of material at the locking part. It will also be seen that by means of the slits 2 and 3 that the corner of the shingle may be bent to form locking tongues of various lengths and shapes, since the slits may be cut at different distances from the sides of the shingle element.

The line 26 represents the line at the bottom or lower edge of the roof.

It will be noticed that each shingle is secured by four nails and that the locking tongues secure each shingle at spaced points.

It would be necessary to destroy each lock in order to disengage the adjacent shingle. Also that the breaking of one locking tongue 45 will not destroy the efficiency of the other remaining locking tongues. As the locking tongues are at right angles to the shingles the tension is therefore in two directions. It is also possible by varying the size and position of the locking tongues 9 and 10 so that when the shingles are laid the overlap of the edges of one shingle over the one below may

be varied in order to properly protect the joints.

This construction of nailing and locking the edges of each shingle together makes the roof when completed, lay flat without bulging up at the locking points.

What I claim is:

1. A shingle having a corner part thereof notched and slotted, the slits extending beyond the inner corner of the notch to provide integral butt locking and foldable tongues, parallel with the side edges of the shingle, said tongues being spaced from the corner of the shingle when folded whereby when a plurality of the shingles are assembled in overlapping relation, the said tongues will engage the adjacent edges of the lower layer of shingles at substantial distances from the apices of the adjacent lower shingles to permit the lower edges of the lower shingle to be elevated for the insertion of the folded tongues and for aligning the shingle, as described.

2. A flexible shingle element formed with intersecting slits which are parallel to the adjacent sides of said element and extending past their intersecting points whereby the material of the shingle may be bent backward and parallel with the adjacent side to form a locking tongue.

3. A shingle element formed with intersecting slits at an angle to the adjacent sides of the shingle and extending past their intersecting point, whereby the material of the shingle may be bent backward parallel with the adjacent sides to form locking tongues, as described.

4. A rectangular shaped shingle element that is formed with a rectangular shaped cut away portion at one corner, the body part of the shingle element having slits which extend inwardly from the inner corner of the cut away portion to permit the material of the body part to be folded inward and parallel to the body part for forming locking tongues for aligning purposes when the shingle elements are assembled and which folded tongues are located under the lower edge of an underlying shingle element at a distance from its corner portion.

NEWELL R. BARTLETT.
